UNITED STATES PATENT OFFICE.

PAT EAKIN, OF SUNLAND, CALIFORNIA.

AMUSEMENT DEVICE.

Application filed July 6, 1925. Serial No. 41,811.

This invention relates to an amusement device and the object is to provide means by use of which children or adults may obtain considerable exercise and especially may 5 obtain for themselves and for observers much amusement by endeavoring to maintain an upright position on a rotatable and longitudinally movable device such as a drum or barrel mounted on a horizontal 10 shaft or bar.

A further object is to provide, in connection with the foregoing, a safety net into which the user of the device will fall without injury in the event that he is unable 15 to maintain his equilibrium.

A still further object is to provide power operated means for imparting movement to the drum or barrel.

With the foregoing and other objects in 20 view, the invention consists in the novel construction and arrangement of elements described, illustrated and claimed, it being understood that modifications may be made within the scope of the claims without de- 25 parting from the spirit of the invention.

In the drawings forming part of this application:

Figure 1 is a view of the construction in 30 elevation, the longer side of the apparatus being shown.

Figure 2 is an end elevation.

Figure 3 is a detail in section showing 35 means for connecting a cable or rope to the drum or barrel mounted on the horizontal shaft.

Figure 4 is a detail view, in perspective, showing a ring for effecting the above named connection between the end flange, shown in Figures 1 and 3, and the cable.

Figure 5 is a view in elevation showing a 40 structure similar to that illustrated in Figure 1, but with means added for applying power to the movement of the drum or barrel on the horizontal shaft.

In carrying out the invention, I provide 45 a base of suitable construction, designated 10, and at opposite ends thereof I provide uprights 11 and 12 mounting bearings in which horizontal shaft or bar 14 is rotatably 50 supported. The bearings are shown in detail in Figure 1 in which a broken away portion of one standard permits the showing of the bearing in vertical section. Inner and outer plates 15 and 16 are positioned on 55 opposite sides of the standard, and are connected by means of bolts 17, and the sleeve

or race-way 18 surrounds the shaft 14 and also surrounds a series of rollers 19, forming a roller bearing.

On this shaft 14 a barrel or drum 20 is 60 mounted, this element being slidable longitudinally of the shaft and being rotatable thereon. End flanges, or flanged portions 21' provide means for receiving and retaining a ring element, or elements 21, of the 65 type shown in Figure 4.

Pulleys 23 and 24 are mounted respectively in the end standards or uprights, and cables or ropes 25 and 26 pass over these 70 pulleys, are connected at their inner ends with ring members 21, and at their outer ends have connection with ring members 28 and 29, by means of which the barrel 20 may be moved by an assistant or by a boy friend. 75

The user of the device endeavors to maintain his equilibrium on the rotatable and slidable barrel 20, and as an aid in doing this a guide rope or cable 30 is provided, one end passing over pulley 31 mounted in 80 one of the standards, this end having a weight 32 connected therewith. An enlargement or knot 33 prevents the cable from passing too far over the pulley 31. The other end of cable 30 extends around 85 pulley 34 and passes thence downwardly and has connection with a weight 35. The weights tend to keep the rope or cable 30 in the position desired.

In order to facilitate access to the move- 90 able portion of the uprights, stairways are employed, and it will be observed from Figure 2 that a similar upper platform is provided and is designated 38, stairways 39 and 40 leading to the platform from 95 opposite sides of the structure. This arrangement is duplicated at the other end of the uprights. In order that the person attempting to maintain his equilibrium on the barrel may not receive a serious fall, 100 I provide a safety net, designated 42, this net including an outer cable or the like 43 passing through the apertured upper end portions of posts 44, and the rope 43 being held taut by springs 45. Other springs 105 such as those shown at 46 may be located as desired and all of the springs are suitably anchored at their outer or lower ends.

In Figure 5 a structure similar to that in Figure 1 is illustrated, but power operated means are provided for moving the 110 barrel 20 longitudinally of the shaft 14,

It is convenient to employ for this purpose an electric motor 50, the armature shaft of which is extended or has coupled thereto a shaft 51 mounting beveled pinions 52 and 53 which are splined on the shaft, the pinions having connected therewith collars 54 operated by means of lever arms 55 pivoted at 56. These arms are connected by a rod 57 secured to the lever arms by 10 means of pivots and permitting the pinions 52 and 53 to be thrown into mesh with large gear wheel 58. The pinions will be thrown in reverse relation, that is, one will move into mesh with gear wheel 58 when the other moves out of mesh with reference thereto. Lever arms 55 are reversed by means of a cable 60 operated by drum 61 rigid with reference to gear wheel 58. Cable 60 carries enlargements or engaging 15 devices 63 which come into contact with the levers and throw the latter in the required direction for effecting a reverse drive. Cable 60 passes over lower pulleys 64 and 65 and over upper pulleys 66 and 67 and 20 passes thence horizontally, the end portions being connected at 68 and 69 with devices similar to ring members 21 of Figure 4. It will be apparent that when the drum 61 has moved cable 60 to a given extent, one of 25 the engaging devices 63 will come into contact with the adjacent lever arm 55 and will cause the reverse of the driving mechanism by means of the construction described in detail. The reverse movement of drum 61, after it has reached its limit of travel, 30 will be effected in a similar manner.

The barrel 20 serves the purpose of a seat or saddle member of unusual construction, and the manner of mounting this seat is a 35 distinctive feature of the invention.

Having thus described the invention what is claimed as new, is:—

1. In a device of the class described, a supporting structure, a rotatable shaft 45 mounted horizontally thereon, and a slideable member mounted on the shaft and adapted to support a person, a rotatable member, devices adapted to engage the rotatable member at diametrically opposite 50 points, and means having connection with and automatically controlled by the position of the slideable member for shifting the en-

gaging devices, in reverse relation, into and out of contact with the rotatable member.

2. In a device of the class described, a 55 supporting structure, a shaft mounted horizontally thereon, and a rotatable and slideable member mounted on the shaft and adapted to support a person, and tension operating means connected with the slideable 60 member and non-rotatable with reference thereto.

3. In a device of the class described, a supporting structure, a rotatable shaft 65 mounted horizontally thereon, a slideable member mounted on the shaft and adapted to support a person, and intermittent power operated means for imparting longitudinal movement to the slideable member, said means including flexible devices, extending 70 from the rotatable member, and mechanically controlled winding means for the flexible devices.

4. In a device of the class described, a supporting structure, a rotatable shaft 75 mounted horizontally thereon, a slideable member mounted on the shaft and adapted to support a person, and means including cables automatically and alternately placed under tension for imparting longitudinal 80 movement to the slideable member.

5. In a device of the class described, a supporting structure, a rotatable shaft mounted horizontally thereon, a slideable member mounted on the shaft and adapted 85 to support a person, and power operated means including automatic reversing mechanism for imparting movement to the slideable member.

6. In a device of the class described, a 90 supporting structure, a rotatable shaft mounted horizontally thereon, a slideable member mounted on the shaft and adapted to support a person, and reversely extending 95 cables connected with the slideable member for imparting longitudinal movement thereto, with reference to the shaft, and a winding element engaged by both cables and applying tension to the cables alternately.

In testimony whereof I affix my signature.

PAT EAKIN.
